UNITED STATES PATENT OFFICE.

WILLIAM CUNNINGTON, OF ROCKPORT, MISSOURI.

TEETH-EXTRACTOR.

SPECIFICATION forming part of Letters Patent No. 225,110, dated March 2, 1880.

Application filed December 20, 1879.

To all whom it may concern:

Be it known that I, WILLIAM CUNNINGTON, of Rockport, in the county of Atchison and State of Missouri, have invented certain new and useful Improvements in Foot-Power Tooth-Drawing Machines; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a perspective of my foot-power tooth-drawing machine, and Fig. 2 is a sectional detail view.

My invention relates to a foot-power tooth-drawing machine; and it consists in the construction of parts, as herein fully described, and particularly pointed out in the claims.

In the drawings, A designates a standard mounted upon a base, B, which is provided with elongated feet C.

D designates a rod, which is mounted in the upper end of the standard A, and in practice it is adjusted in position within a hollow part of said standard by means of a set-screw, a. E is a foot-rest, which is connected with one of the feet C by a sliding hinge, so as to accommodate its position to the position of the operator. F is a lever-bar, pivoted at one end to the base B, and provided at its free forked end with a pulley-block, f, and a pivoted foot-lever, f', formed with the curved ends f² f³, the longer one, f², being for the pressure of the operator's foot, and the shorter one, f³, being arranged to act against the cord which passes round the pulley-block f when the longer end of said lever is depressed. G is a foot-rest upon standard A, and is used for the operator to place one foot upon preparatory to depressing the foot-lever, thus maintaining the foot in a convenient position for instantaneous use.

The cord H is secured to the standard at I, and from thence passes around the pulley-block K of a weight, K', after which it passes around a pulley-block, K², secured to the standard, and thence down through an opening in a guide-block, L, secured upon the standard A. After passing down through this guide-block it is carried round the pulley-block of the le-

ver-bar F, which is to be depressed by the action of the foot upon its pivoted foot and clamping-lever f'. After this the cord passes up alongside of a pulley-block, M, and through an opening in the guide-block L, thence over a pulley-block, N, and finally out to and over a pulley-block, O, from which it drops down, and has secured upon its end the forceps-holder P.

The pulley-blocks N and O are carried by a horizontal arm, Q, the block N being pivoted directly to the inner end of the said arm, while the remaining pulley-block, O, is pivoted to a weighted arm, R, which is swiveled upon the end of arm Q.

The weight K' forms a counterpoise for the pulley-block O, whereby the forceps-holder may be the more readily moved by hand to various positions.

The arm Q is swiveled upon the rod D, so that it may be shifted up and down or around; and to secure it in place I form the rod with two or more lines of holes, D', and provide the arm with a spring, S, having on its end a pin, S', which is forced into one of said holes by spring-pressure.

During operation the operator secures forceps to the forceps-holder, which may have spring-jaws or any suitable means for such purpose, and then places one foot upon the rest E, to steady the machine, and his other foot upon the rest G. After applying the forceps to the patient's tooth, he slips his foot down from rest G upon the curved foot-lever, and thence, by depressing the same, the short curved arm of said foot-lever will press against the cord around pulley f to keep it from slipping, and the lever F will be brought down, thereby tightening up the cord between said lever and the forceps sufficiently to extract the tooth. After releasing the lever the weight will restore the cord to its normal position between said weight and lever, and will also draw up the forceps-holder out of the way.

The forceps, during operation, may be placed in any required position, and may be turned round as required, while at the same time there will be a great strain upon them, owing to the depression of the lever by foot-pressure.

What I claim is—

1. In a machine for drawing teeth, the hinged sliding foot-rest E, connected with one of the

supporting feet of a standard which carries the manipulating devices, substantially as set forth.

2. In combination with the cord passing over 5 a series of pulleys and carrying at one end a device for connecting with forceps, the lever F, provided with a foot-lever, f' , substantially as set forth.

3. The foot-lever F, pulley-block f , and the 10 foot-lever with curved ends $f^2 f^2$, substantially as set forth.

4. The foot-rest G, in combination with the foot-lever f' , as specified.

5. The cord H, weight K', guide-block L,

pulley-block K ^{2} , foot-lever f^2 , pulley f, stand- 15 ard A, and arm Q, with pulleys N and O, ar- ranged substantially as set forth.

6. The arm Q, pulleys N and O, and weighted 20 swiveled arm upon the end of arm Q, as set forth.

In testimony that I claim the above I have hereunto subscribed my name in the presence of two witnesses.

WILLIAM CUNNINGTON.
